United States Patent Office

Des. 195,259

Patented May 21, 1963

195,259

GIRDLE

Mario Laguzzi, Long Island City, N.Y., assignor to Poirette Corsets, Inc., New York, N.Y.

Original design application Jan. 31, 1962, Ser. No.
68,593, now Patent No. Des. 193,776, dated Oct. 9,
1962. Divided and this application July 11, 1962, Ser.
No. 70,876

Term of patent 14 years

(Cl. D20—2)

FIG. 1

FIG. 2

This application comprises a division of my copending application entitled Girdle, Ser. No. D. 68,593, filed January 31, 1962, now Patent Number D. 193,776.

I claim:

The ornamental design for a girdle, as shown and described.
